UNITED STATES PATENT OFFICE.

EMILY W. THAYER, OF SAXTONS RIVER, VERMONT.

DESIGN FOR A STOCKING-DARNER.

No. 38,887.

Specification for Design.

Patented Nov. 19, 1907.

Application filed May 29, 1907. Serial No. 376,453. Term of patent 14 years.

To all whom it may concern:

Be it known that I, EMILY WAITEE THAYER, a citizen of the United States, residing at Saxtons River, in the county of Windham and State of Vermont, have invented a new, original, and ornamental Design for Stocking-Darners, of which the following is a specification, reference being had to the accompanying drawing, forming part thereof.

The figure is a perspective view of a stocking darning, showing my new design.

I claim:

The ornamental design for a stocking darning, as shown.

EMILY W. THAYER.
